Primary Examiner — Rosemary K Tarcza(74) *Attorney, Agent, or Firm* — Dennis A. Bennett; Gale Starkey(57) **CLAIM**

The ornamental design for a personal emergency response device charging base, as shown and described.

DESCRIPTION

FIG. 1 is a front perspective view of a personal emergency response device charging base showing my new design; FIG. 2 is a back perspective view thereof; FIG. 3 is a front elevation view thereof; FIG. 4 is a left side elevation view thereof; FIG. 5 is a right side elevation view thereof; FIG. 6 is a top plan view thereof; FIG. 7 is a bottom plan view thereof; and, FIG. 8 is a back elevation view thereof. The broken line disclosure is for illustrative purposes only and forms no part of the claimed design.
